UNITED STATES PATENT OFFICE.

JAMES ROURKE, OF INDEPENDENCE, KANSAS.

WELL-DRILLING MACHINE.

No. 854,606.

Specification of Letters Patent.

Patented May 21, 1907.

Application filed November 22, 1905. Serial No. 288,592.

To all whom it may concern:

Be it known that I, JAMES ROURKE, a citizen of the United States, residing at Independence, in the county of Montgomery and State of Kansas, have invented certain new and useful Improvements in Well-Drilling Machines, of which the following is a specification.

This invention relates to well drilling machines and it has for an object to provide means whereby the bull wheel and the casing-rope reel may be driven from a shaft which drives the walking beam, without operating the walking beam.

Other and further objects will appear in the following description and will be more particularly pointed out in the appended claims.

In the drawings, Figure 1 is a side elevation of my machine, Fig. 2 is a top plan view, and Figs. 3 and 4 are detail views of the pitman connecting the crank shaft and the walking beam, Fig. 5 is a detail showing the sand rope reel operating lever, and Fig. 6 is a front elevation of the derrick.

The main frame of the machine, which may or may not be supported on wheels, consists of the side sills 1 and 2, the end sills 3 and 4, transverse sills 5 and 6, a longitudinal sill 7 connecting end sill 4 with transverse sill 6, and a longitudinal sill 8 connecting end sill 3 with transverse sill 5.

A gas or other engine 9 is supported on the rear end of the frame on sills 1 and 7 and has its pitman 10 connected to a cranked shaft drive 11 which is journaled on sills 1 and 7 and projects at both ends from the side of said sills.

Upon the inner projecting end of the drive shaft 11 is keyed a fly wheel 12 with which a wheel 13 on a sand reel 14 is adapted to frictionally engage to be driven thereby and consequently draw in the sand rope, the shaft 15 of the reel being so mounted that it 45 may be swung by lever 16 to permit this engagement. The shaft may also be swung so that wheel 13 may be thrown into engagement with a fixed brake face 17 on sill 4.

Upon the outer projecting end of the drive shaft 11 is mounted a drive pulley 18 which by means of belt 19 is connected to driven pulley 20 keyed to a projecting end of a crank shaft 21. The crank shaft 21 is connected to the walking beam in a manner, hereinafter to be described, and is supported by a pair of frames upon the sills 1 and 8.

Each of these frames comprises a pair of posts 22 seated at their lower ends in recesses in the sills, and connected at their upper ends by a beam 23, bolts 24 passing through the sill, the posts and the beam to hold the parts together. Upon these beams are bolted the journals for the shaft 21, the journals being also held to the beams by straps 25 which pass over the journals and are secured at their ends by the bolts 24. Brace straps 26 are also held at their upper ends by the bolts 24 and are secured at their lower ends to one of the sills 1 or 8.

Sprocket wheels 27 and 28 are loosely journaled upon the crank shaft 21 and are adapted to be connected by means of a clutch 29 operated by lever 30, with said shaft, to turn therewith. The sprocket wheel 27 is geared by means of a sprocket chain 32 to a sprocket 75 30^a on a bull wheel 31, journaled on side sills 1 and 2 between the transverse sills 5 and 6, while the sprocket 28 is geared, by means of a sprocket chain 33, to a sprocket 34 on a shaft 35 journaled on the opposite side of 80 crank shaft 21 in sills 1, 2 and 8. Upon this shaft 35 is secured a casing-rope-reel 36 and a brake drum 37 controlled by band-brake 38 and lever 39.

The manner of connecting the crank shaft 85 21 to the walking beam is as follows: The crank shaft carries a crank 40 having a wrist pin 41 adjustable in openings 42. To this wrist pin is connected one end of a pitman 43, the upper end of the pitman being yoked and 90 pivotally connected to one end of the usual walking beam 44 which is pivotally mounted on the upper end of the samson post 45. The pitman 43 is formed to permit the connection between crank shaft 21 and walking 95 beam to be broken so that the shaft may operate either the casing rope reel or the bull wheel. This is accomplished by dividing the pitman into two members 43^a and 43^b, the upper one 43^a being in the form of a yoke and 100 comprising two strips 43^c and 43^d, while the lower one 43^b is pivoted at 44 between the strips and has its upper end notched at 45' and beveled or rounded at 46 on each side of the notch, whereby a sliding bolt 47 moving in slots 48 in strips 43^c and 43^d, may be caused to automatically ride on the rounded ends 46 and drop in notch 45' when the members 43^a and 43^b are aligned. A pin 49 enters notch 50 and limits the pivoting of the 110 members to one direction.

When it is desired to break the connection

between crank shaft 21 and the walking beam, a cable 51, leading from the bolt 47 upwardly over pulley 52 and 53 and downwardly to a point near the bottom of the 5 samson post, is pulled.

The drill rope 54 leads from the bull wheel 31 upwardly over the pulley 55 at the top of the derrick and is engaged by the free end of the walking beam 44 in the usual manner, 10 while a sand rope 56 leads from reel 14 over a pulley 57 located on the side near the top of the derrick. This derrick comprises a pair of spaced parallel standards 58 supported on a base 59 and held by guy ropes or wires 60 leading 15 from the top of the standards to the base. Between these standards is located a standard 61 which supports pulleys 55 and 57 before mentioned, and which is adapted to be clamped between the upper ends of standards 58 by plates 62 which when loosened permit the standard 61 to drop between the standards.

When it is desired to operate the drill rope, clutch 29 is shifted to connect crank shaft 21 25 with sprocket wheel 27 and thus, through chain 32 and sprocket 31, motion is transmitted from shaft 21 to bull wheel 31. Motion is transmitted from shaft 21 to the casing rope reel by means of sprocket 28, chain 30 33, and sprocket 34, and to prevent excessive speed during the lowering of the casing, lever 39 is operated to cause band brake 38 to act on drum 37.

During the operation of the bull wheel and 35 the casing rope reel from the shaft 21, the connection between shaft 21 and walking beam 44 is broken.

Having thus described my invention what I claim and desire to secure by Letters Patent is:

1. In a well drilling machine, the combination with the crank-shaft, of a walking-beam operated thereby, means for breaking connection between the walking beam and the 45 crank shaft, a bull-wheel, a casing-rope-reel, and a clutch mechanism for establishing connection between the crank shaft and the bull-wheel or between the crank-shaft and the casing-rope-reel.

50 2. In a well drilling machine, the combina-

tion of the main frame provided with recesses, posts seated on their ends in said recesses, a beam connecting the upper ends of the posts, bolts passing through the frame, the posts and the beam, a journal bearing bolted to the 55 beam, a strap passing around the journal bearing and secured at its ends to the beam by the bolts that pass through the posts, and brace straps also secured at one of their ends by the bolts and secured to the main frame. 60

3. In a well drilling machine, the combination with the crank shaft and the walking beam, of a pitman connecting said members, and formed of two members adapted to be moved to permit the crank shaft to rotate 65 without rocking the walking beams.

4. In a well drilling machine, the combination with the crank shaft and the walking beam, of a pitman connecting said members, and formed of two members pivoted together, 70 and means holding the members against relative movement.

5. In a well drilling machine, the combination with the crank shaft and the walking beam, of a pitman connecting said members, 75 and formed of two members pivoted together, means holding the members against relative movement, and a controlling rope for said means.

6. In a well drilling machine, the combination with the crank shaft and the walking beam, of a pitman connecting said members, and formed of two members pivoted together, means holding the members against relative movement, and a controlling rope for said 85 means, said means causing the parts to be automatically locked when the controlling rope is released.

7. In a well drilling machine the combination with the crank shaft and the walking 90 beam, of a pitman connecting said members, and formed of two members pivoted together, and means holding the members against relative movement and comprising a sliding bolt on one member adapted to engage the other 95 member.

JAMES ROURKE.

In presence of two witnesses—

I. B. WALLACE,
W. L. CONNELLY.
